UNITED STATES PATENT OFFICE

2,549,806

ELECTRIC FUEL IGNITER

William D. Hall, Elkins, W. Va.

Application April 1, 1947, Serial No. 733,600

5 Claims. (Cl. 219—32)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to igniting devices and more particularly to igniters for coal furnaces.

The main object of this invention is to provide an igniting device that may be inserted in a bed of coal to effectively ignite the same without use of kindling wood. Other objects and advantages of the invention will appear as this description proceeds.

The invention is of broad scope and will be defined generically in the claims. The specific structure involved includes a heating coil suitably protected from damage by a ceramic element. After the coal is heated by the heating coil the flame may be built up by either or both of two additional features, namely (a) a blower for supplying air to the coal, and (b) by passing a heavy current through the coal itself. Further details will appear as this description proceeds.

In the drawings:

Figure 1 is a sectional view of the coal furnace igniter.

Figure 2 is a sectional view of the igniting head taken along line 2—2 of Figure 1.

Figure 3 illustrates the electrical circuit employed in the device.

Referring to Figure 1, a ceramic supporting base 10 of a suitable insulating compound has embedded therein and very close to its outer surface a helical coil 11 of the highest quality heating wire. This wire may be wound within the ceramic base in any suitable manner but preferably should be wound so as to give a maximum temperature at the surface of the base 10 without overheating the wire. Pipe 12 supports the base 10. Electrodes 13 and 14 in the form of rings are mounted at opposite ends of base 10 and are respectively connected in the circuit as shown in Figure 3. The pipe 12 is insulated from contact with any metal parts of any furnace to which it contacts by insulation 15. The pipe 12 carries insulating supporting member 16 which in turn supports conical hood 17. A blower 18 is driven by motor M and propels air down pipe 12. This air is reflected by cone 17 back into the region of the flame initiated by the igniter. Two switches 19 and 20 are respectively in series with the blower motor M and the heater wire 11; and power at 115 volts, for example, is supplied by domestic lighting system 21. The flow of current to rings 13 and 14 may be controlled by switch 19 or by an independent switch if desired;

2

and switch 19 may be an off-on switch or may be a step switch which cuts out a resistance in steps to gradually increase the voltage of the circuit.

5 In order to ignite a bed of soft coal, the conical element 17 is rammed in the bed. It protects the parts 10 to 14 during this operation. The switch 20 is then closed energizing heater wire 11 which in turn heats the soft coal. This heat will not only cause ignition of the coal but will drive out of it a thick liquid.

15 At this point switch 19 may be closed (or in the alternative it can remain closed from the beginning) causing a heavy current to flow from electrode 13 through the coal to electrode 14 thereby generating a very high degree of heat. The blower 18 will propel air down pipe 12 which air is reflected back by cone 17 in to the bed of ignited coals around part 10. Switch 20 may now be turned off. The air from the blower will thereupon build up the flame to a large extent.

20 It is of course possible to omit the electrodes 13 and 14 and allow the heater wire 11 to ignite the coal alone but the process of igniting the coal 25 is somewhat slower under these circumstances and furthermore the heater wire does not last as long. With the electrodes 13 and 14 it is not necessary that the heater wire 11 actually heat the coal to igniting temperature. Heater wire 11 may heat the coal just enough to start conduction through the coal itself. Therefore the heater wire 11 may run cooler than it would necessarily run without the electrodes 13 and 14.

35 When cold, soft coal is not sufficiently conducting to be ignited by merely passing current therethrough from ordinary domestic power sources. However, if the coal is preheated by heater wire 11, it may be ignited from domestic lighting circuits by passing current directly through the coal.

40 I claim to have invented:

1. An igniter for soft coal comprising an elongated pipe, a blower at the first end of the pipe for forcing air through the pipe, an electric motor for driving the blower, a circuit for energizing the motor, a switch in said circuit, a ceramic base carried by said pipe at the second end thereof, an igniting wire embedded in said base for raising the latter to igniting temperature, said ceramic base covering said igniting wire to insulate the wire from electrical contact with the coal, a pair of spaced electrodes mounted on said base, wires connecting said electrodes respectively across opposite sides of said circuit, and a conical hood of larger diameter than the pipe and mounted on the second end of said pipe for deflecting

the air therefrom back to the second end of the pipe and across said base.

2. An igniter for solid fuel comprising an element of insulating material, a handle for the element enabling the latter to be rammed into a bed of coal, a heating wire covered by said element and insulated mechanically and electrically from contact with the fuel for heating the element, spaced electrodes adjacent the element and arranged to contact the heated fuel, and means for applying sufficient electrical potential across said electrodes to cause sufficient current to pass through the heated fuel to ignite the same.

3. An igniter for a bed of soft coal comprising a block adapted to be rammed into a bed of coal and having a continuous ceramic surface, a heating wire embedded in the block for heating said surface to thus render coal adjacent the surface conducting, spaced electrodes adjacent the surface for passing current through the coal adjacent said surface, means for supplying current to the electrodes through a path independent of the heating wire, said means including means for supplying sufficient current to said electrodes for a sufficient time duration to ignite coal, a blower for blowing air into the bed of coal after the latter has been ignited, said blower having an air output duct, a hollow handle supporting said block at one end of the handle, and means connecting the blower to the other end of the handle and said duct to feed the hollow handle at that end of the handle that connects to the blower.

4. An igniter for soft coal as defined in claim 2 in which said insulating material is the only element that separates the wire from contact with the coal.

5. An igniter for soft coal as defined in claim 2 designed to operate from an outlet of domestic electric power in which the wire has such high resistivity that when it is connected across said outlet it is heated to a temperature below the ignition point of the coal, said electrodes being so closely spaced that when connected across said outlet they will pass sufficient current directly through the coal to ignite it after the coal has 10 been heated by said wire.
